DRAFT EVENER.

APPLICATION FILED OCT. 24, 1905.

UNITED STATES PATENT OFFICE.

HINRY THIEDEMANN AND JURGEN HENRICH THIEDEMANN, OF HICKMAN,
NEBRASKA.

DRAFT-EVENER.

No. 819,097.

Specification of Letters Patent.

Patented May 1, 1906.

Application filed October 24, 1905. Serial No. 284,177.

To all whom it may concern:

Be it known that we, HINRY THIEDEMANN and JURGEN HENRICH THIEDEMANN, citizens of the United States, residing at Hickman, 5 in the county of Lancaster and State of Nebraska, have invented new and useful Improvements in Draft-Eveners, of which the following is a specification.

Our invention is a draft-evener, and has 10 for its object simplicity of construction and efficiency of operation; and to this end it consists in certain novel features of construction hereinafter described and claimed.

In the accompanying drawings, Figure 1 is 15 a plan view of the invention. Fig. 2 is an edge view thereof. Fig. 3 is a plan view showing the position of the parts when turning a corner.

Referring specifically to the drawings, 20 10 denotes a plow-beam, and 11 the clevis thereof to which the evener is attached. The supporting-frame of the evener comprises spaced top and bottom plates 12 and 13, respectively, which are fastened together by bolts 14, 15, and 16. The bolts 14 and 15 are near the ends of the frame, and the bolt 16 is located between said ends. The frame is connected to the plow-clevis by bars 17 and 18, respectively. The bar 17 extends to and is 25 made fast to the end bolt 14. The bar 18 is formed with two arms or branches 19 and 20, respectively. The arm 19 extends to and is made fast to the end bolt 15, and the arm 20 extends to and is made fast to the intermediate bolt 16.

At 21 is indicated an evener-bar which is pivoted on the bolt 16 between the top and bottom plates of the supporting-frame. Each end of the evener-bar is shaped so that 30 40 arc-shaped slots 22 and 23, respectively, are formed, which slots are for a purpose to be described hereinafter.

An evener-lever 24, carrying a doubletree 25, extends between the supporting-frame 45 and is pivoted to the end bolt 14. On this same bolt an angle-lever 26 is pivoted, said lever having at one end a rearwardly-extending arm 27, which is connected by a link 28 to the evener-lever 24. Preferably the lever 26 50 and link 28 are in pairs, as shown. The end of the angle-lever 26 opposite the arm 27 carries a bolt 29, which extends through and works in the slot 22.

A second evener-lever 30, carrying a doubletree 31, is pivoted on the end bolt 15. The 55 short arm of this lever extends between the supporting-frame and carries a bolt 32, which extends through and works in the slot 23. The lever 30 has a number of holes 33, in which the attaching means of the doubletree 60 31 are secured, so that the leverage can be adjusted.

The evener can be reversed and worked on either the right or left side, and by the use of a trebletree it can also be used as a five-horse 65 evener. The teams are held to a straight pull, there being no side draft, and the draft is evenly distributed. Upon turning a corner the parts by reason of the engagement of the bolts 29 and 32 in the slots 22 and 23 of 70 the evener-bar assume the position shown in Fig. 3, so that the teams are pulling at almost a right angle to the plow, which facilitates making the turn. After the turn is made all parts readily assume their normal position, 75 the slots 22 and 23 being so shaped that no binding of the parts will take place. The evener will also readily operate upon making a turn to the right. To further enable the parts to move freely without binding, the 80 bolts 29 and 32 can be fitted with friction-rollers. The evener can also be applied to a harvester and when so applied will effectively take up all side draft.

Having thus described our invention, what 85 is claimed as new, and desired to be secured by Letters Patent, is—

1. A draft-evener comprising a supporting-frame, an evener-bar pivoted in said frame and formed with arc-shaped slots in its 90 ends, a pair of evener-levers pivoted on opposite sides of the evener-bar and operatively connected, respectively, at their inner ends to the slots in the evener-bar.

2. A draft-evener comprising a supporting-frame, an evener-bar pivoted in said frame and formed with arc-shaped slots, a pair of evener-levers pivoted in said frame and carrying at their inner ends bolts which work, respectively, in the slots of the evener-bar.

3. A draft-evener comprising a supporting-frame, an evener-bar pivoted in said frame and formed with arc-shaped slots in its ends, an evener-lever and an angle-lever pivoted in said frame on a common pivot, said

angle-lever being connected at one end to the
evener-lever, and its other end being opera-
tively connected to one of the slots in the
evener-bar, and a second evener-lever piv-
oted in the supporting-frame and operatively
connected to the other slot of the evener-bar.

In testimony whereof we have signed our

names to this specification in the presence of
two subscribing witnesses.

HINRY THIEDEMANN.

JURGEN HENRICH THIEDEMANN.
